CLOSURE FOR DISPENSING CONTAINERS

Clarence Philip Corriveau, Manchester, N. H.

Application April 11, 1950, Serial No. 155,249

1 Claim. (Cl. 222—516)

1

This invention relates to closures for dispensing containers and more especially to a self-closing cap for dispensing containers such as toothpaste tubes or tooth powder cans, although the closure may be used for a multitude of different purposes with different type of receptacles.

It is an object of this invention to provide a closure member for a dispensing container comprising a self-closing cap having means thereon for opening the same to permit the contents of the container to be dispensed through the cap and being so constructed as to automatically close when the opening means is released by an operator.

It is another object of this invention to provide a closure member of the type described having a base member adapted to be secured to a suitable container and also having a cover member adapted to fit over and slidably engage the base member, said base member having a peripheral groove therein in which a compression spring is disposed, and said cover member having a projection thereon adapted to fit into the peripheral groove in the base member and to engage one end of the compression spring, so that the compression spring will normally hold the cover member in closed position, that is, so that the bore therein will not coincide with the bore in the base member. The cover member is also provided with an operating handle thereon which may be engaged by an operator to move the cover member to where the bore therein will coincide with the bore in the base member to thereby permit the contents of the container to be emitted through the bores, and whereby, upon releasing said handle, the compression spring will cause the cover member to return to its original position to automatically close the top of the container.

It is another object of this invention to provide a closure of the type described wherein the base member has a peripheral groove of the type described in which a compression spring is loosely disposed and said base member also being provided with a second peripheral groove on the opposed side thereof, and the cover member being provided with a projection adapted to fit into the second peripheral groove, and the second peripheral groove being so disposed as to properly guide the cover member to cause the bore in the cover member and the base member to coincide when the cover member is moved to open position.

Some of the objects of the invention having

2

been stated, other objects will appear as the description proceeds when taken in connection with the accompanying drawings, in which—

Figure 1 is a top plan view of the improved closure member associated with a can such as a tooth powder can and showing same in closed position;

Figure 2 is a side elevation of the closure member shown in Figure 1;

Figure 3 is a sectional plan view taken along the line 3—3 in Figure 2;

Figure 4 is a side elevation of the closure member with the top or cover member removed therefrom;

Figure 5 is a sectional plan view of the closure member in open position and is taken along the line 5—5 in Figure 2;

Figure 6 is a vertical sectional view taken substantially along the line 6—6 in Figure 3 but showing the closure member associated with a pliable container such as a toothpaste tube;

Figure 7 is a side elevation of the closure member showing the same associated with a pliable container such as a toothpaste tube.

Referring more specifically to the drawings there will be observed a pliable tube 10 and a rigid can 11, which are shown for purposes of illustration only, the improved closure or self-closing cap being adapted to be used with any type of container, the only modification necessary being in size and in the manner in which the cap is attached to the container. The cap comprises a base member 12 which is suitably secured to a top 13 of a rigid container such as a can, as by fusing, or the base member 12 may be formed integral with the top of the container 13. When the base member 12 is associated with the pliable tube 10 the base member 12 may be provided with a flange 14 for suitably securing the same to the tube 10 as by fusing or a pressed fit.

The base member 12 is circular in plan and is provided with a top portion 15 and a continuous side wall 16 and the top portion 15 has a bore 17 therein.

The continuous side wall 16 of the base member 12 is provided with peripheral grooves 20 and 21 disposed on opposed sides thereof, the peripheral groove 21 extending around a greater portion of the periphery of the base member 12 than the peripheral groove 20. The grooves 20 and 21 are provided for purposes to be presently described. A projecting rib 22 extends around the periphery of the base member 12 adjacent the lower portion thereof, and this rib 22 is adapted

to fit into an internal peripheral groove 25 formed in a flange 26 of a cover member 27, said cover member 27 also being provided with a top portion 28. The cover member 27 is circular in plan and has a bore 30 therein of the same diameter as the bore 17 in the base member 12, and is located the same distance from the center of the cover member 27 as the bore 17 is located from the center of the base member 12 so the two bores will coincide when the cover member is rotated in a counterclockwise direction in Figure 3 and that the bores 30 and 17 do not coincide with each other when the cover member 27 is in the position shown in Figure 1.

The cover 27 is adapted to fit over and slidably engage the side walls of the base member 12 and the cover 27 is held in place by the internal peripheral groove 25 fitting over the peripheral projection 22 of the base member 12. The base member 12 as well as the cover member 27 may be made of any suitable material such as metal, plastic and the like, and the material should be of such a nature and the peripheral flange 22 of such a size as to permit the cover member 27 to be placed over the base member 12 and to permit force to be applied on the cover member 27 to cause the flange 26 to move downwardly so that the groove 25 will snap into position over the projection 22. The peripheral groove 25 is slightly larger than the peripheral projection 22 to permit the cover member 27 to rotate on the base member 12.

The cover member 27 is also provided with a suitable handle or lever 31 on the exterior thereof of adapted to be engaged by the thumb or hand of an operator to rotate the cover 27 upon the base member 12.

The cover member 27 has projections 32 and 33 on the internal periphery thereof diametrically opposed to each other and the projection 32 is adapted to fit in the peripheral groove 20 and the projection 33 is adapted to fit in the peripheral groove 21 in the base member 12. A vertical slot 34 having its upper end flush with the top 15 of the base member 12 communicates with the groove 20 and a similar slot 35 communicates with the groove 21 to permit the projections 32 and 33 to fit into the grooves 20 and 21 when the cap is assembled. A compression spring 36 is loosely disposed in the peripheral groove 21 with one end thereof adjacent the end wall of the groove 21 and the other end of the compression spring 36 is adapted to be engaged by the projection 33.

It will thus be observed that when it is desired to open the container, the handle 31 may be moved in a counterclockwise direction causing the cover member 27 to rotate in a counterclockwise direction so that the projection 33 will bear against the compression spring 36 compressing the same and the projection 32 will move freely in the peripheral groove 20 until it engages the end wall of the peripheral groove 20 or reaches the position shown in Figure 5. At this time, the bore 30 in the cover member will be in alignment with the bore 17 in the base member to permit the contents of the container to be dispensed through said bores, the projections 32 and 33 also serving to guide the cover member as it is rotated on the base member 12. Upon release of the handle 31 by the hand of an operator, the compression 70 spring 36 will urge the projection 33 and the cover member 27 in a clockwise direction to move

the bore 30 out of alignment with the bore 17 to automatically close the container.

It is thus seen that there is provided a self-closing cap member particularly adapted to be used with small containers such as tubes, cans and the like and which may be stamped or molded from any suitable material such as plastic or metal and may be readily secured to the top of the container to permit the same to be easily opened by pressure of the thumb of an operator on the lever 31 and whereby the same will close automatically when the lever 31 is released by the operator.

In the drawings and specification there has been set forth a preferred embodiment of the invention, and although specific terms are employed, they are used in a generic and descriptive sense only, and not for purposes of limitation, the scope of the invention being defined in the claim.

I claim:

A self-closing cap for a container comprising a base member having a top portion and a continuous side wall and being substantially circular in plan, a cover member having a top portion and a continuous side wall adapted to fit over and oscillatably engage the outer surface of said base member, said base member having a peripheral projection extending therearound, said cover member having a groove on the interior thereof adapted to fit over the peripheral projection on said base member to permit the cover member to rotate on the base member, said base member having a bore disposed in off-center relation therein, said cover also being provided with a bore so positioned as to coincide with the bore in the base member, the side wall of said base member having peripheral grooves disposed one in each side thereof, said base member having a pair of vertically disposed grooves extending from the top thereof, said vertically disposed grooves being disposed 180 degrees from each other and each vertically disposed groove communicating with one end of a peripheral groove, spring means loosely disposed in one of said peripheral grooves, said cover being provided with a projection on each side thereof adapted to be passed through the vertically disposed grooves and into the peripheral grooves in said base member, one of said projections being adapted to engage one end of the spring means, said spring means normally urging the cover member to a position where the bore therein is out of communication with the bore in said base member, and said cover member having a protuberance thereon adapted to be engaged by an operator to move the same against the pressure of said spring means to cause the bore in the cover member to coincide with the bore in said base member, said projections and said peripheral grooves also serving to guide the cover member as it is rotated.

CLARENCE PHILIP CORRIVEAU.
